UNITED STATES PATENT OFFICE.

WILLIAM H. STEVENS, OF ALTOONA, PENNSYLVANIA.

APPARATUS FOR USING POWDERED FUEL.

1,316,399.

Specification of Letters Patent. Patented Sept. 16, 1919.

Application filed March 31, 1916. Serial No. 37,982.

To all whom it may concern:

Be it known that I, WILLIAM H. STEVENS, a citizen of the United States, residing at Altoona, in the county of Blair and State of Pennsylvania, have invented certain new and useful Improvements in Apparatus for Using Powdered Fuel, of which the following is a specification.

The invention relates to apparatus for using powdered fuel such as coal and the like. The invention has for its primary objects the provision of an improved powdered fuel utilizing means, (1) which can be advantageously applied in locomotive practice, (2) which can be applied without a wide departure from standard locomotive construction, (3) which provides for an exceedingly long travel of the burning fuel and products of combustion thus insuring complete combustion and a minimum temperature of the gases before they leave the fire-box, and (4) which utilizes the heat of the smoke box to increase the efficiency of the apparatus. Certain embodiments of the invention are illustrated in the accompanying drawings wherein—

Figure 1 is a longitudinal section through a locomotive boiler equipped with my invention; Fig. 2 is a front end elevation of the construction; Fig. 3 is a side elevation of the feeding means used in connection with the construction of Fig. 1; Fig. 4 is a section through a smoke-box equipped with a modified construction; and Fig. 5 is a front view of the construction of Fig. 4, the end plate of the smoke-box being removed in both Figs. 4 and 5.

Referring to Fig. 1, the reference numeral 1 indicates a locomotive boiler provided at the front end with the smoke box 2 and at the rear end with the fire-box 3, the smoke and fire boxes being connected by the usual fire-tubes 4. The fire-box preferably is substantially closed, a refractory wall 5 constituting the bottom of the fire-box.

Extending longitudinally of the boiler and smoke box are the corrugated combustion flues 6, such flues being preferably two in number although this may be varied to meet requirements. These flues are preferably lined with a refractory coating 8 and have their rear ends opening into the fire-box while their front ends are turned downwardly as indicated at 9 and receive the ends 55 of the coal supply pipes 10.

These coal supply pipes preferably lead

to the tender and are provided with coal feeding means of the type indicated in Fig. 3. Air is supplied to the tubes 10 by means of a fan 11 operated from a motor, not shown, and coal is supplied to the tubes 10 by means of the screw conveyers 12 leading from the hopper 13. The front ends of the tubes 10 are extended into the ends of the flues 6 in the form of nozzles 14, and a space 65 is preferably provided between the down-turned ends of the flues and the tubes 10, thus permitting an inflow of air at these points.

If desired an additional supply of fuel 70 may be provided in the fire-box by means of the pipes 15 leading from the pipes 10 and entering the front end of the fire-box at the lower side thereof. These pipes are provided with cutoff valves 16 for controlling 75 or cutting off the supply of coal and air so that this supply means may be regulated or thrown out of action as desired.

The construction provides for a long path 80 for the burning fuel and gases so that a thorough combustion is insured, and a maximum amount of heat is abstracted from the gases before they pass into the fire-tubes. Part of the combustion occurs in the flues and 85 part in the fire-box, and the flues serve to add to the heating surface of the furnace. The fan for feeding the coal can be made 90 relatively small since the draft from the locomotive smoke box produces a suction in the fire-box and in the flues tending to draw 95 the air and coal through the tubes 10 and thus reducing the work required from the fan. The passage of the flues through the smoke-box 2 increases their efficiency since a considerable amount of heat is absorbed 96 from the hot gases therein. Other advantages incident to the construction will be apparent to those skilled in the art.

Figs. 4 and 5 illustrate a modification 100 wherein an air heating pipe 17 is provided in the smoke box 18. This air heating tube has an inlet end 19 leading from the atmosphere outside the smoke box and has two discharge ends 19' (Fig. 5) leading into the flues 20, the flue construction in other particulars being the same as that in Fig. 1. The coal is brought to the ends of the flues 105 20 by means of the tubes 21 leading through the extensions 22 of the flues, the outer ends of these extensions being closed as indicated 110 at 23. This arrangement adds somewhat to the efficiency of the device since the air which

is utilized for combustion in the flues 20 is highly heated in the pipe 17 which coils back and forth in the highly heated smoke box.

5. What I claim is:

1. The combination with a locomotive boiler having a smoke box, a fire-box and the usual connecting fire-tubes, of a relatively small combustion flue extending

10 through the smoke box and then longitudinally through the boiler beneath the fire-tubes and opening into the fire-box, means for supplying a mixture of powdered coal and air to the front end of the flue, and a

15 supplemental air inlet to the flue at the front end thereof.

2. The combination with a locomotive boiler having a smoke box, a fire-box and the usual connecting fire-tubes, of a relatively small combustion flue extending

20 through the smoke box and then longitudinally through the boiler beneath the fire-tubes and opening into the fire-box, a powdered coal and air supply pipe leading for-

25 wardly from the rear end of the boiler and discharging into the forward end of the flue, and a supplemental air inlet to the flue at the front end thereof.

3. The combination with a locomotive boiler having a smoke box, a fire-box and the usual connecting fire-tubes, of a rela-

tively small combustion flue extending through the smoke box and then longitudinally through the boiler beneath the fire-tubes and opening into the fire-box, means 35 for supplying a mixture of powdered coal and air to the front end of the flue, and other means for supplying supplemental quantities of the mixture of powdered coal and air into the front end of the fire-box. 40

4. The combination with a locomotive boiler having a smoke-box, a fire-box and the usual connecting fire-tubes, of a relatively small combustion flue extending through the smoke-box and then longitudinally through the boiler beneath the fire-tubes and opening into the fire-box, said combustion flue being of corrugated formation and lined with refractory material, and means for supplying a mixture of powdered 50 coal and air to the front end of the flue.

5. The combination with a locomotive boiler having a smoke-box, a fire-box and the usual connecting fire-tubes, of a relatively small combustion flue extending 55 through the smoke-box and then longitudinally through the boiler beneath the fire-tubes and opening into the fire box, and means for supplying a mixture of powdered coal and air to the front end of the flue.

WILLIAM H. STEVENS.
